UNITED STATES PATENT OFFICE.

JOHN WILIAM HOEFLERS, OF CHICAGO, ILLINOIS.

EXTENSIBLE MOLD-FLASK.

SPECIFICATION forming part of Letters Patent No. 726,290, dated April 28, 1903.

Application filed February 9, 1903. Serial No. 142,517. (No model.)

To all whom it may concern:

Be it known that I, JOHN WILIAM HOEFLERS, a citizen of the United States, residing at Chicago, Cook county, Illinois, have invented 5 certain new and useful Improvements in Extensible Mold-Flasks, of which the following is a specification.

This invention relates to molders' flasks, and has particular reference to flasks which 10 may be increased or diminished in dimensions to meet varying requirements in a foundry, especially where a large variety of casks are made.

In a general foundry, where the work is not 15 confined to any particular kind of castings, or even in a specialty foundry, where many different parts are made, a large variety of molding-flasks must be kept on hand, which take up a great deal of room, entail considerable loss of time in their assortment and 20 handling, and even then the ordinary and adequate supply of a given size of flask at times fails to meet special demands.

The object of my invention, therefore, is to 25 provide an expandable or extensible flask which may be quickly reduced or increased in size to meet special requirements when a regular given size is exhausted.

Another object of the invention is to effect 30 a great saving in the number of flasks required to be kept regularly on hand, thereby not only saving the first cost of a large number of reserve flasks, but effecting a material saving of room or space. The latter is a very 35 important item where the available space is limited or ground rentals high.

Another object of the invention is to avoid loss of time, not only in hunting up a given size of flask, but to obviate the necessity of 40 delaying the casting of certain molds for the release of suitable flasks already in use and to save the time often lost by one molder being obliged to wait for another to get through with his flask before he can undertake a certain and perhaps immediately-pressing job. The number of different sizes of flasks kept on hand in foundries usually ranges from twenty-five to one hundred, and then, of course, the quantity of each size must be 45 limited in number. As probably less than one-third of these flasks are in use at any one time, my invention will make it possible to

dispense with, perhaps, approximately the other two-thirds. Furthermore, even where a large number of sizes of flasks are kept on hand it is not possible to place a large number of workmen upon a single kind or size of casting, because the supply of any one given size is necessarily very limited.

My invention makes it possible to, within 60 certain reasonable limitations of size, place all of the molders at work turning out a rush order for one kind of casting, which in a "job" foundry is oftentimes even more important than the great saving of upward of 65 two-thirds of the number of sizes of flasks required to be kept on hand.

Generally speaking, my invention consists in a flask having its ends and sides made in two parts, which may be separated for the 70 insertion of a suitable extension-piece.

The invention further consists in a flask having each of its sides and ends divided and the divided portions mortised into each other, so as to provide a universal joint for 75 one or more extension-pieces, and means for securing together said sides and ends with or without said extension-pieces.

The invention further consists in a novel combination male and female extension-piece 80 or joint; and the invention further consists in the various details of construction and combinations of parts, all as hereinafter more fully described, and particularly pointed out in the claims.

My invention will be more readily understood by reference to the accompanying drawings, forming a part of this specification, and in which—

Figure 1 is a perspective view of a molding-flask embodying my invention. Fig. 2 is a detail illustrating one part of the coupling or joint member of the separable adjacent ends of the flask proper. Fig. 3 is a perspective view of the extension-piece, the respective ends of which are made to fit the parts shown in Figs. 2 and 4. Fig. 4 is a detail illustrating the opposite joint member adapted to fit the part shown in Fig. 2 and one end of Fig. 3. Fig. 5 is a reduced top plan view 100 of the flask.

In the drawings, 2 represents the bottom board provided with cleats 3 of the usual design, upon which is placed the flask 4, em-

bodying my invention. The flask 4 comprises the corner-pieces 4', the long side pieces 5 5', the short side pieces 5' 5', and the ends 6 6', all in duplicate for the top and bottom or 5 "cope" and "drag" portions. The adjacent ends of the sides 5 5' and ends of end pieces 6 are provided, respectively, with the female joint member 7, Fig. 4, and male joint member 7', Fig. 2, which fit each other and the respective ends of the extension-piece illustrated in Fig. 3, and which is provided with fittings 7" and 7'', which are substantially similar to the fittings 7 7'. The joint members 7' and 7'' have tenons or lugs 8 and the members 7 and 7''' mortises or recesses 9 for said lugs or tenons. The members above referred to have apertures 10, 16, and 10', the last named being threaded for the connecting-rods 11, with which it has a screw engagement. The rods 11 have heads 11', adapted for wrench engagement. As the joint members are preferably castings, I prefer to provide the female member 7 with bosses 12, which constitute threaded nuts or reinforcements for the threaded apertures 10'. The joint members 7 7' 7'' 7''' are also provided with small screw or nail holes 13 for screws 13', which enable their being secured to the respective ends of the extension-piece 14, side pieces 5 5', and end pieces 6. The extension-piece 14 is adapted to fill the gap 14' (shown in Fig. 1) between the ends of side pieces 5 and 5', and, exactly similar, but preferably narrower, extension-pieces are provided to 35 fill in the spaces shown between ends of end pieces 6 and the corner-pieces 4'. The adjacent ends of side pieces 5 5' and end and corner pieces 6 and 4' are represented by the respective ends of the extension-piece 14, (illustrated in Fig. 3,) except that in the side pieces 5 and the ends 6 there are no threaded holes 10' or side apertures 16. It will therefore be noted that with a supply of not more than one or two sizes of such extension-pieces 14 45 a given size of flask may be changed in size within quite a large range of adjustment. These extension-pieces are provided with channels or grooves 16 in their one side for the rods 11. By providing these channels in 50 the side of the extension-piece the latter may be inserted or removed without removing the rods 11. In the side pieces 5 are provided holes 17, (shown by dotted lines,) at the outer ends of which are the bosses 12. Corresponding holes are provided in the ends 6, with the exception that in the latter the holes extend through and the rods 11 have no threaded engagement therein, but move freely therethrough, the threaded engagement for rods 55 60 61 being provided for in the joint members in the corner-pieces 4'.

In Fig. 1 I have shown a gap between the end piece 6 and both the corner-pieces 4', whereby provision is made for extension both 65 ways from the end pieces 6, which arrangement I prefer on account of the pin 18 and socket 19, which I have provided in the up-

per and lower end piece 6, respectively. The object of this double extension is to keep the pin-and-socket interlocking means central, so 70 as to keep the flask centrally balanced on this connection in order that on a straight lift the upper part of the flask will not tip with relation to the lower part.

In the foregoing description I have made 75 no separate reference to the top and bottom parts of the flask, or what is known as the "cope" and "drag," respectively, this by reason of the fact that these parts are exactly alike, with the exception that in the Fig. 1 80 illustration I have shown a T-shaped recess 20 to provide for extension of the flask as to depth, also by means of bolts 21 and threaded plates or nuts 22, which are adapted to fasten a strip 23 upon each of the sides and ends of 85 the flask. While I have shown this recess by way of a simple illustration of the idea only in the cope portion, it is obvious that the drag may also be recessed for similar extension downwardly, and preferably so when 90 the parts of the flask are made in large quantities, where it is desirable that said parts shall be alike and interchangeable.

At one corner of the flask I preferably provide clasps, consisting of hooks 24 and pin- 95 plates 25 and hinges 26 at the diagonally opposite corner of the flask, (see Fig. 5,) whereby the flask may be opened and handled exactly as the ordinary "snap-flask."

As any of my flasks can be almost if not 100 quite doubled in dimensions with the use of a single set of rods 11, it is apparent that it will perform the service of at least three fixed sizes, with the additional advantage of being always available for either of said sizes without the loss of time incident to searches for proper sizes. As the extension-pieces are interchangeable, a large number of them may be stacked up in a small space where available to all the workmen in a foundry. The 110 usual metal-edge straps may be provided, as well as fittings, made of iron or brass, and, with the exception of rods 11, cast or otherwise. It is obvious that the "upsets" may be matched in the same manner as the extension-pieces 14. It is also obvious that the end pieces 6 need not be extended at both ends, as shown, and that they may be added to exactly as the sides 5, and it is further obvious that numerous modifications may be 120 made in the minor details of my invention by one skilled in the art without departing from the spirit thereof, and I therefore do not confine my invention to the specific construction herein shown and described. 125

Having thus described my invention, I claim as new and desire to secure by Letters Patent—

1. An extension-flask, having divided side portions and independent extension-pieces 130 fitting in between and flush with the sides of said side portions, and means common to all of said portions and pieces for securing same together.

and ends composed of a plurality of separate jointed sections, each of the adjacent ends of the individual side or end section being provided with a joint member adapted to fit into 5 one of the joint members of one of the other sections, a threaded connecting-rod for the sections of each side or end having threaded engagement with one section of said side or end and adapted to clamp together the sections of said side or end and including within 10 said clamp the end of an adjacent side or end section, and separate means for locking the opposite adjacent side or end upon the opposite end of said side or end sections.

15 22. A molder's flask having each of its sides and ends composed of a plurality of jointed and apertured sections, each of the adjacent ends of each individual side or end being provided, respectively, with a male and a female 20 joint member interlocking said adjacent ends

and said joint members being adapted to fit into or interlock with the joint members of other sections of said sides or ends, a threaded clamping-rod for each side and end, said rod being provided with a turning-head and 25 having threaded engagement with one section of said side or end and adapted to clamp between its said head and threaded section one or more separate sections of one said side or end together with a section of another adjacent side or end and means for interlocking the opposite side or end with the other adjacent side or end.

In testimony whereof I have hereunto set my hand, in the presence of two witnesses, 35 this 4th day of February, 1903.

JOHN WILLIAM HOEFERS.
